UNITED STATES PATENT OFFICE.

ALEXANDER SIEWERT, OF BERLIN, GERMANY.

EXTENSION AND RETRACTION DEVICE.

1,073,294.

Specification of Letters Patent. Patented Sept. 16, 1913.

Application filed April 6, 1911. Serial No. 619,361.

To all whom it may concern:

Be it known that I, ALEXANDER SIEWERT, a subject of the King of Prussia, and residing at Bernburgerstrasse 24-25 Berlin, Germany, have invented certain new and useful Improvements in Extension and Retraction Devices, of which the following is a specification.

This invention relates to a mechanism for 10 the extension of telescoping masts and other extensible and retractable supports and lifting apparatuses.

It consists in causing the separate telescoping parts provided with internal threading to be extended consecutively upon a spindle placed in the interior of the mechanism.

Apparatuses are already known in which 20 platforms and the like are raised by turning spindles. It has nevertheless not previously been possible to construct in this manner masts and the like the length of which considerably exceeds twice the length of the lifting spindle. By the present invention, masts and the like can be extended by aid of a spindle the length of which need only be a fraction of the height of the extended mechanism.

The invention is illustrated in the drawings in two figures, of which—

Figure 1 is a longitudinal elevation, and Fig. 2 a section on the line A—A of Fig. 1.

The telescopic parts *b*, *b'* and *b''* are arranged in a casing *c* and their extension is 35 effected by means of a spindle *a* revolvably supported in the foot of the casing, which spindle has a rather greater length than that of each separate tube. The lower part of the spindle is without threading. The tubes 40 are provided at their lower end with internal threading, which with the exception of the innermost tube *b* is out of engagement with the spindle threading when the mast is retracted. On turning the spindle *a* by 45 means of the threading *e*, first the innermost tube *b* is raised, until it strikes with an annular projection *f* against the projection *g* of the tube *b'* surrounding it. It then carries this tube with it so that the matrix 50 thereof engages with the spindle *a* and then leaves the spindle inasmuch as it has been bolted to the aforesaid tube *b'* by means of an automatic locking device. For this purpose, holes *h* are provided in the tubes, 55 which coincide with one another when the

lower projection *f* of the then inner tube has struck against the upper projection *g* of the tube surrounding it. On the tubes is placed in slot *i* a pin *k* which is pressed into the coinciding holes *h* by a spring *l* as soon as the head of the pin *k* has quitted the slot *m*.

In order that the rising telescopic part may not carry with it the other telescopic part surrounding it by aid of friction, there is passed through all the parts, with the exception of the innermost, a pin *d*, the inner end of which is rounded off. The rising tube presses this pin by means of its projection *f* outward to the extent of the thickness of one tube and thereby liberates the tube immediately surrounding it. The telescopic parts may have a circular or polygonal section, and the tube walls may be composed of net work.

The arrangement according to the present invention is adapted especially for the construction of jacks especially for automobiles for the purpose of which a corresponding diminution of the height dimensions must take place.

The spindle *a* instead of being revolvably supported in a casing *c* can be rigidly connected therewith and then by revolving this casing the spindle can be turned and thereby the extension of the telescopic parts be effected. In this case the casing *c* is preferably supported by ball bearings upon a separate bed plate and moreover provided with spokes or with holes for the insertion of bars.

Having now particularly described and ascertained the nature of my said invention and in what manner the same is to be performed, I declare that what I claim is:

A device of the kind described comprising in combination an outer casing, a number of telescopic parts in said casing, a screw spindle placed in the interior of said telescopic parts, means for rotating said screw spindle, a female screw at the bottom-end of each of said telescopic parts and adapted to engage the screw-threaded portion of said screw-spindle, a spring-governed bolt at the upper end of each of said telescopic parts adapted to engage a hole in the adjacent inner telescopic part before the latter leaves the top of said screw-spindle, means for disengaging said spring-governed bolts when said telescopic parts are retracted, and a spring 110

governed bolt connected with said casing and adapted to project through all said telescopic parts with the exception of the innermost and to be pressed outward by the rising telescopic part to the extent of the thickness of one of said telescopic parts, substantially as set forth.

In witness whereof I have hereunto signed my name this 23rd day of March 1911, in the presence of two subscribing witnesses.

ALEXANDER SIEWERT.
